RADIO EQUIPMENT

Filed Jan. 28, 1926

Alfred Ernest White INVENTOR

UNITED STATES PATENT OFFICE.

ALFRED ERNEST WHITE, OF PASADENA, CALIFORNIA.

RADIO EQUIPMENT.

Application filed January 28, 1926. Serial No. 84,520.

The invention relates to means of fixing any and all radio equipment including that for transmitting and receiving so that the filaments of the tubes may be heated either by alternating or direct current whereby as applied to receivers eliminates the great expense of dry cells for this purpose or the expense and constant care of a charger and special storage battery because almost every user is already provided with alternating current for lighting his residence and a storage battery in his automobile, and wherein in connection with my means of filament supply reliable and economic operation is provided both for home and motor camping service.

I accomplish this as shown in the accompanying drawing. As no plugs are shown inserted in the jacks J_1 and J_2 , the set is now indicated as operating its speaker 12 with the tube filaments heated from 110 volt AC service using the transformer 9, but if it is inconvenient to use this service or if very clear signals are desired for use of ear phones, a standard phone plug bearing DC current may be inserted in the jack J_1 , which will automatically and accurately perform all necessary changes in the connections for the set to properly use the DC filament supply. Now returning to the operation of the set with the AC supply it is to be noted that on jack J_1 the spring-blade 2 is making contact with 3 and the spring-blade 5 is making contact with 4 thus putting the voltage of the transformer 9 onto the tube filaments and the grid return of 5 of the first audio transformer 14 through the "C" battery 7. Now let us change to the DC filament supply by inserting the above-mentioned phone plug bear-

ing the DC voltage into the jack J_2 , and it will be noted that this insertion will automatically disconnect one terminal of the AC transformer 9 by forcing the spring-blade 2 away from 3 and the point of the plug bearing the DC positive and its sleeve the DC negative, puts the DC voltage onto the filaments with correct polarity through the frame 1 and spring-blade 2 of this jack less any desired loss in voltage by the separation of 1 from 6 on the resistance 8. The insertion of this plug also separates 4 from 5 and connects 5 with 1 through the sleeve of the plug thus now making the grid return 5 of the audio transformer 14 to the negative filament wire. It is understood that this plan can also be used in other circuits and equipment than the simple one here illustrated and considering the foregoing that which I claim to have invented is:

In a radio receiving circuit comprising one or more vacuum tubes having filaments adapted to be energized from either an alternating or a direct current source and grid electrodes, means for applying alternating current to said filaments comprising a transformer the secondary of which is shunted by a potentiometer, means for connecting said grid electrodes to a point on said potentiometer, a multi-contact jack connected between the filaments and the transformer, a plug adapted to be inserted in said jack connected to a direct current source for opening the circuit between the filaments and the transformer and for connecting the grid electrodes to the negative pole of the direct current source when the plug is inserted in the jack.

ALFRED ERNEST WHITE.
